UNITED STATES PATENT OFFICE.

ELMER APPERSON, OF KOKOMO, INDIANA, ASSIGNOR TO APPERSON BROS. AUTOMOBILE COMPANY, OF KOKOMO, INDIANA, A CORPORATION OF INDIANA.

DESIGN FOR AN AUTOMOBILE-BODY.

48,359.

Specification for Design.

Patented Jan. 4, 1916.

Application filed August 6, 1915. Serial No. 44,121. Term of patent 7 years.

To all whom it may concern:

Be it known that I, **ELMER APPERSON**, a citizen of the United States, residing at Kokomo, in the county of Howard and State of Indiana, have invented a new, original, and ornamental Design for Automobile-Bodies, of which the following is a specification, reference being had to the accompanying drawing, forming a part thereof.

In the drawing—Figure 1 is a plan view

of my improved automobile showing the new design; and Fig. 2 is a side elevation of the same showing the new design.

I claim:—

The ornamental design for an automobile body, as shown.

ELMER APPERSON.
